UNITED STATES PATENT OFFICE

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA

VERTICAL RETORT OVEN

Application filed March 20, 1926. Serial No. 96,238.

This invention relates in general to improvements of general utility in construction of coke ovens and more particularly to improvements in construction of vertical retort structures such as exemplified in my prior copending application Serial No. 684,342, filed January 4, 1924, for vertical retort structure, and the invention has for an essential object the provision of a joint intermediate 10 adjacent section, said joint extending from the retort oven or chamber to the outer walls of said sections so that should there be any leakage through the joint, such leakage can be readily stopped by pointing up the outer 15 faces of the joint. A further important object of the invention is the provision and location of such a joint so that there will be no possible chance of leakage from a regenerator chamber into a coking chamber 20 or from a coking chamber into a regenerator chamber; the provision and arrangement of such a joint, between sections of the structure, which is so located and arranged that no great amount of brickwork or structure 25 need be torn out in order to reach and stop a leak through the joint, and the invention has for further objects such other improvements and advantages in construction and operation as may be found to obtain in structure hereinafter described or claimed.

In the accompanying drawings, forming a part of this specification, and showing, for purpose of exemplification, a preferred form and manner in which the invention may be 35 embodied and practiced, but without limiting the claimed invention specifically to such illustrative instance or instances:—

Figure 1 is a composite horizontal sectional view taken in the different horizontal planes 40 of a vertical retort coking structure embodying the present invention as indicated by the section lines BB, CC, and DD of Figs. 2 and 3.

Fig. 2 is a vertical sectional view taken on 45 the line 2—2 of Fig. 1.

Fig. 3 is a composite vertical sectional view taken in different vertical planes as indicated by the section lines EE, GG, and HH of Figs. 1 and 2.

50 In its present embodiment, the invention

is incorporated in a vertical retort structure for producing metallurgical coke, such as that exemplified in my aforesaid copending application, Serial No. 684,342, filed January 4, 1924, for vertical retort structure, such structure being one that is especially designed for the employment of the combination oven principle involving the alternative use of an extraneously derived relatively lean gas, or with a relatively rich gas for fuel. 55 For convenience, the present invention will be described in connection with such structure. The invention, however, is capable of other valuable applications, for example, to apparatus generally useful in the heat treatment of materials, or to constructions providing for heating solely with relatively lean gas according to the "gas oven" principle, or to constructions providing for heating solely with relatively rich gas according to 60 the "coke oven" principle.

Referring to the drawings, there are shown views of a vertical retort battery of the by-product type, as hereinbefore mentioned. The vertical retort battery comprises in its 75 construction a series of distilling chambers, such as the series 11 of vertically elongated retorts or coking chambers, the retorts of the series being contiguous to the intermediate heating walls 12. The heating walls 80 12 form the side walls of the respective retort chambers 11, both being preferably substantially rectangular in horizontal section and elongated transversely of the battery structure but relatively narrow longitudinally of 85 the battery, as shown in Fig. 1. The heating walls and the retort chambers extend to a great height as compared with their horizontal dimensions, and the retorts 11 are tapered toward the top as shown in the section EE 90 of Fig. 3, to facilitate passage of the material being treated from top to bottom of the retort.

The series of retorts and corresponding intermediate heating walls are respectively 95 arranged and extend along one side of the battery assembly, as shown in Fig. 1, whereas the regenerators extend along the other side of the battery assembly. The outer ends of the respective retorts as well as the heating 100

walls are closed by the side refractory wall structure, indicated at 15, and the other or inner ends of the said heating walls and coking chambers are separated from the series of regenerators by the interior refractory wall structure 16, as shown in Figs. 1 and 2. The outer ends of regenerators are closed by the side refractory wall structure 17.

10 The coal to be coked is charged into the upper ends of the retorts 11 and the completed coke is discharged through openings at the bottom of the said retorts.

Because of the great height of the retorts 15 as compared with their horizontal dimensions, the retort battery is preferably employed as a continuous vertical retort, with consequent great capacity for coke and by-product production. When so employed a 20 continuous feed of carbonaceous material may be maintained through the retorts 11, with continuous discharge of the finished coke from the bottoms of such retorts.

The heat for coking the charges of coal in 25 the several retorts 11 is derived from the heating walls 12 corresponding to said retorts. Each heating wall 12 is constituted of a plurality of upper flue sections 37 and a plurality of lower flue sections 38 and 30 the former are connected with the latter in such manner as to form continuous vertical flue passages extending from top to bottom of the heating walls, as is more fully and particularly described in my aforesaid application Serial No. 684,342, and to which attention is hereby expressly directed for more detailed references as to construction and operation of such structure and for details of the flue arrangement and flow connections.

40 As shown in Fig. 2, the flue sections 37 and 38 are of substantially equal length, the flue sections 38 extending upwardly to a horizontal plane substantially midway the 45 top and bottom of the heating wall, and the upper flue sections 37 extend from said lower flue sections 38 to the top 39 of the battery structure. At their bottoms the lower flue sections 38 of each of the heating walls 50 are respectively connected by ports 42 with a horizontal channel 43 located in the bottom of the heating wall. The horizontal channel 43 located in the bottom of one heating wall is connected with the horizontal 55 channel 43 of the next adjacent heating wall by a passageway 44 which crosses around the intermediate retort chamber through the outer refractory wall structure 15. By this arrangement the bottoms of the burning lower 60 flue sections 38 are connected with the bottoms of upflow lower flue sections 38 in the next adjacent heating wall, by means of said passageways 44 which convey the waste gases from the former to the latter flue sections.

The regenerators 45 are located on that

side of the battery opposite the retorts 11 and heating walls 12 and are separated from said retorts and heating walls by the interior wall structure 16.

As shown in Fig. 1, the regenerators are 70 located in a single series along one side of the battery with the major vertical plane of the regenerators parallel to the major vertical planes of the retorts and heating walls. Operatively, the series of regenerators 75 45 is arranged into two groups R and S, each group comprising four regenerators. The regenerators of the group R alternate with the regenerators of the group S, as shown in Fig. 1. When the several regenerators 80 of the groups R are operating for inflow, that is to say, for delivering preheated gaseous media to the flues of the heating walls, the several regenerators of the other groups S are operating for outflow to extract heat 85 from the gases discharged into the regenerators from the flues. On reversal of the battery, at the end of each operating period, the inflow regenerators become outflow regenerators and the outflow regenerators become 90 inflow regenerators.

95 Each regenerator 45 is preferably a high narrow upright chamber, substantially rectangular in horizontal cross section and containing open brickwork or checkerwork 46 having a sole channel 47 underneath the opening up into the checkerwork. Advantageously, ledges 48 are provided in the walls of the regenerators in order to support the checkerbrick as a plurality of stacks of checkerbrick so that should it be necessary to enter the regenerators the entire amount of checkerbrick need not be torn out.

100 Each regenerator A whether of the group R or of the group S leads at its upper end 105 into a duct 53, which duct 53 is directly connected with the horizontal flues 54 at the top of the heating wall 11 corresponding to said regenerator. In like manner, each regenerator P, whether of the group R or S, leads at 110 its upper end into a duct 63 directly connected with the horizontal channel 64 at the top of the heating wall corresponding to said regenerator.

115 Each heating wall 11 has a pair of such horizontal channels 53 and 63 leading respectively from regenerators A and P of the group corresponding to said heating wall. The horizontal channel 53 of each heating wall is directly connected with the tops of the several upper flue sections 37 by ports 55; and the horizontal channel 64 is likewise directly connected with the tops of said upper flue sections 37 by ports 65.

120 Connections are also provided for leading 125 gaseous media, for instance, air and producer gas, from the tops of the inflow regenerators directly to the tops of the lower flue sections 38 of the downflow operating heating walls. Referring particularly to Figs. 1 and 3, the 130

horizontal channels 54 of each heating wall are connected by a series of ducts 71 with a series of vertical feed channels 72 located in the alternate bottle-bricks 73 between the flue channels. Similarly the horizontal channels 64 of each heating wall are connected by a series of ducts 81 with a series of vertical feed channels 82 located in the bottle bricks 83 intermediate the alternate bottle bricks 73. As shown in Fig. 2, the alternate feed channels 72 and intermediate vertical feed channels 82 extend down through the bottle bricks to the bottoms of the upper flue sections 37 and channels 72 and 82 of each adjacent pair are provided with ducts 74 and 84 which converge into and through the nozzle blocks 41 at the top of the lower flue section 38.

In operating with extraneously derived gas, such as producer gas, the structure provides supply connections to the tops of each downburning lower flue sections 38 for permitting producer gas and air regenerators P and A to propagate additional flame in the downburning lower flue sections. Any waste gases from the upper flue 37 together with the waste gases from the bottom of the lower flue sections 38, of the downburning heating walls, pass through the ports 42 into the horizontal channels 43 in the bottoms of the downburning heating walls and thence through the cross-around passages 44 into the similar channels 43 of the upflow operating heating walls. From the channels 43 of the upflow operating walls the waste gases pass through the ports 42 and thence upwardly through the sections 38 of said walls. At the tops of the lower flue sections 38 the waste gases discharge through the said passages 40 and ducts 74 and 84 into the upper flue sections 37 and feed channels 72 and 82, and pass therethrough and out at the tops of the upflow operating heating walls into the horizontal channels 54 and 64 through which the waste gases are conveyed to the waste gas regenerators WW. Passing downwardly through the regenerators the waste gases heat up the checkerbrick for the next inflow operating period of said regenerators.

Provision is made for operating the battery alternatively with a relatively rich gas, such as coke oven gas, and for supplying said gas to the tops of both the upper sections 37 and the lower sections of the continuous downburning vertical flue channels. As shown in Fig. 3, the vertical coke oven gas ducts 91 lead through the top 39 of the battery structure respectively into the tops of the upper flue section of each heating wall.

Within each nozzle block 41 is a vertical coke oven gas duct 93 provided with a nozzle 94 set into the tapered upper portion of the duct. The vertical ducts 93 lead directly into the tops of the lower flue sections 38 for the purpose of supplying coke oven gas

to the tops of such flue sections as are operating for downflow combustion. The ducts 93 are supplied with coke oven gas from horizontal supply channels 95, which extend lengthwise through the respective heating walls 12, as shown in Fig. 2, and intersect all of the nozzle blocks 41. The channels 95 may be supplied at 96 with gas from a coke oven gas main.

Such operating structures are subjected to very high heat, such as from 1500° to 1800° C., and consequently as they are brought up to operating temperatures, they expand and unless some provision or allowance is made for expansion, they will be subjected to stresses and strains which might and can cause crackling and rupturing of the masonry of which they are constructed. In accordance with the present invention the structures hereinbefore referred to are designed and constructed so as to constitute adjoining expandible sections which when expanded are substantially contiguous to each other with an expansion joint between each section, said joint extending from the retort chambers 11 to the outer ends of the sections, so that should there be leakage through any joint the gas will escape to the outer atmosphere and so that such leak can be readily stopped by pointing up the particular leaking joint from near the outer walls of the battery. Advantageously the battery is built so as to be constituted of expandible sections 96, each consisting of a flued heating wall 12 closed at one end by the refractory wall 15 and at the other end by the interior refractory wall 16 and regenerators 45, said sections being built adjacent each other so that the adjoining sections together form coking chambers 11 between their respective heating walls 12. The regenerator end of each section 96 is connected with its adjoining section by an expansion joint 97 extending from the retort 11 to the outer walls 15 and 17, said joints extending vertically from the bottoms of the heating walls and regenerators to their tops. The adjacent surfaces of adjoining walls 16 are connected by vertically extending tongue and groove expansion joints 98 by reason of the vertical extending tongues 99 and 100 of one heating wall extending into vertically extending grooves 101 and 102 in an adjacent wall 16, and from there the joint extends in a straight line between the adjacent walls 103 of adjoining regenerator chambers. At the other end of the retort, the expansion joint is constituted of a staggered joint 104. As the brickwork is being laid to form the sections, spacing material, usually strawboard, is placed between adjacent sections to maintain sufficient space for expansion. After the sections are heated up the strawboard disintegrates and permits the adjacent sections to make contact with each other. The expanded tongue and groove joints 98 are filled in with 125

a filling material, preferably that material known as thermolith. After the structure is heated up the outer faces of the expansion joints are packed with asbestos rope, indicated at 105, and pointed and then the outer pinion walls are enclosed by facing brick.

From the foregoing description it will be apparent that the invention provides a novel expansion joint for such structures that may 10 be readily sealed from the outside without requiring entry into the regenerator chambers and that there is no chance of leakage of gas through any expansion joint from a retort into a regenerator chamber or from a regenerator chamber into a retort or any of the 15 flues.

The invention as hereinabove set forth is embodied in particular forms but may be variously embodied within the scope of the 20 claims hereinafter made.

I claim:

1. In a coke oven structure, the combination of a row of sections; each of said sections comprising a vertically flued heating 25 wall, a wall at one lateral end of said heating wall, and walled regenerators individual to said heating wall and in communication with the flues therein; said regenerators being arranged at the opposite end of said heating 30 wall and having their side walls parallel with said heating wall; said sections being disposed adjacent each other and together forming vertical retort coking chambers between the heating walls; each section being connect- 35 ed for expansion with an adjacent section by an expansion joint extending from the coking chamber to each of the outer ends of said section.

2. Apparatus as claimed in claim 1, characterized by there being a tongue and groove joint in said expansion joint.

3. In a vertical retort oven, in combination; a plurality of vertical coking chambers; heating walls contiguous to said chambers and 45 comprising combustion flues; regenerators in communication with said combustion flues and individual to each of said heating walls and arranged at lateral ends thereof; and expansion joints extending through the walls 50 at each end of each coking chamber from the coking chambers to the outside of the oven.

4. In a vertical retort battery, in combination: a plurality of high narrow retort chambers, each adapted to receive through its top 55 a charge to be coked and adapted to discharge through its bottom the coked charge; heating walls contiguous to said retort chambers and respectively constituted of combustion flues; high narrow regenerators serving the flues of the heating walls respectively; channels communicably connecting the regenerators with the flues of their respective heating walls; and expansion joints in the walls 60 of said battery, said joints extending from 65

each end of the retort chambers to the outside of the battery.

5. In a coke oven structure, in combination: walls forming coking chambers and having heating flues therein; individually regulable 70 regenerators for the heating walls; duct means communicably connecting the regenerators with the flues of said heating walls; duct means communicably common to and connecting for flow a plurality of flues in one 75 wall with a plurality of flues in another wall; and expansion joints in the walls of the structure extending through walls between regenerator chambers from each coking chamber 80 to the exterior of the structure.

6. In a vertical retort oven structure, in combination: a group of vertical coking chambers; flued heating walls contiguous to said chambers; regenerators therefor and arranged alongside said group of coking chambers; and expansion joints extending through walls between regenerator chambers from the coking chambers to the outside of the structure. 85

7. A structure as claimed in claim 6, characterized by the expansion joints being staggered joints. 90

8. A structure as claimed in claim 6, in which the regenerators are in adjoining sections each comprising a plurality of regenerators, and in which the expansion joints are between the walls of adjoining regenerator sections. 95

9. A vertical retort construction comprising, in combination: a plurality of adjoining sections; each section comprising a flued heating wall and walled regenerators at one lateral end thereof and in communication with a plurality of flues therein and an end wall at the opposite end thereof; adjacent sections together forming a vertical retort between the heating walls of said sections, each section being connected with its adjoining section to accommodate expansion and contraction by an expansion joint extending from the retort to the outer walls of a plurality of regenerators; and a cross-around duct in said end wall, said duct communicably connecting a plurality of flues in one of said heating walls with a plurality of flues in another of said heating walls. 110

10. In a coke oven structure, the combination of a row of sections; each of said sections comprising a structural unit comprising a flued heating wall, and walls at each end of said heating wall; said sections being disposed adjacent each other and together forming vertical retort coking chambers between the heating walls; each section being connected for expansion with an adjacent section by an expansion joint extending through the walls at each end of the heating walls from the coking chamber to the outer ends of said section. 120 125 130

11. A vertical retort construction comprising, in combination; a plurality of adjoining sections; each section comprising a structural unit comprising a flued heating wall and walls at the opposite ends of said heating wall; adjacent sections together forming a vertical retort between the heating walls of said sections, each section being connected with its adjoining section to accommodate 5 expansion and contraction by an expansion joint extending through adjacent walls at each end of the heating walls from the retort to the outer ends of adjacent sections; and a cross-around duct in adjacent walls at one 10 end of the heating walls, said duct communicably connecting a plurality of the flued heating walls.

In testimony whereof I have hereunto set
my hand.

JOSEPH VAN ACKEREN.
